RECEIVING APPARATUS FOR COMMUNICATION SYSTEMS

Warren M. Adams, Kokomo, Ind., assignor to The Union Switch and Signal Company, Swissvale, Pa., a corporation of Pennsylvania

Application March 4, 1942, Serial No. 433,266

2 Claims. (Cl. 250—20)

My invention relates to receiving apparatus for communication systems, and more particularly to receiving apparatus for systems using an oscillating current.

Communication systems frequently require an amplifier of one or more stages, and in systems using an oscillating current such as a modulated carrier current one or more stages of high frequency amplification are employed ahead of the demodulator which in turn is followed by one or more stages of low frequency amplification. Such receiving apparatus is often provided with automatic volume control to insure a substantially uniform energy level output.

A feature of my present invention is the provision of receiving apparatus for communication systems incorporating a novel and improved electron tube amplifier provided with means for controlling the amplifier gain and the volume of the output energy.

Another feature of my invention is the provision of improved automatic volume control means whereby the grid current of the tube of one stage of a receiving amplifier is used to control the amplification gain of the tube of one or more stages ahead of such one stage, as well as to control the amplification gain of such one stage.

Still another feature of my invention is the provision of improved automatic volume control means whereby distortion of the output energy is minimized. Other features, objects and advantages of my invention will appear as the specification progresses.

The features, objects and advantages of my invention are attained by arranging the receiving apparatus to cause the grid of the tube of a pre-selected one of the stages to swing positive in potential with respect to its cathode during at least a portion of the positive half cycles of the input energy above a preselected normal value, so that grid current flows. A control unit including a condenser is interposed in this grid circuit and the flow of grid current charges the condenser, the stored voltage being proportional to the value of the grid current, and in turn proportional to the magnitude of the input energy. This stored voltage is fed back onto the grid of the tube of one or more of the earlier stages as a bias voltage to control the gain at such earlier stages. Furthermore, such stored voltage is effective to control the bias voltage of the associated tube. I also provide a manually operable biasing means for readily adjusting the receiving apparatus at the predetermined point at which the automatic control unit is to become effective. I provide in

addition a manually operable means to adjust the magnitude of the voltage applied to the final stage of the amplifier so that the output volume of the usual loud speaker can readily be controlled.

I shall describe one form of apparatus embodying my invention, and shall then point out the novel features thereof in claims.

In the accompanying drawing, Fig. 1 is a diagrammatic view showing one form of apparatus embodying my invention when used in the receiving apparatus for a carrier telephone system. Figs. 2, 3 and 4 are diagrams illustrating operating characteristics of the apparatus of Fig. 1.

Apparatus embodying my invention is peculiarly suitable for use in receiving apparatus for railway train communication systems in which a carrier telephone current is employed, and energy is received on a train inductively from a wayside transmitting circuit which circuit usually includes the track rails. For example, in such a train communication system, the carrier may be of the order of 5700 cycles per second and the voice frequencies of 400 to 2500 cycles per second, while a single side band only is transmitted, whereby the wayside transmitting circuit conveys a carrier telephone current of the frequency range of 6100 to 8200 cycles. The attenuation of the current is relatively high due to the rail impedance, ballast leakage and other operating conditions so that the energy picked up by the receiving means mounted on the train in inductive relation to the wayside circuit varies between relatively wide limits due to the constant change in the position of the train with respect to the sending station and due to the constant change in conditions of the transmitting circuit. Because the received current is at times of a very low energy level, a relatively high gain amplifier is required in the receiving apparatus with the result that when the received current is relatively large in magnitude the response of the train carried loud speaker or telephone receiver may be so loud as to be annoying. Furthermore, since the receiving apparatus is normally conditioned for reception, the earth currents and stray magnetic fields may produce noise of a volume that is annoying during non-communication periods because of the high gain of the amplifier. Although apparatus embodying my invention thus has peculiar utilities in such railway train communication systems, my invention is in no manner limited in its use to railway train communication systems and such application is cited as

an illustration of the many places where apparatus embodying my invention is useful.

Referring to Fig. 1, the receiving apparatus is shown as including two stages of high frequency amplification, a demodulator and a single stage of low or audio frequency amplification as well as a receiving unit and a loud speaker. The reference character IC indicates a receiving unit for picking up energy from a sending station, not shown. In radio systems, the receiving unit IC would be an antenna and in railway train communication systems of the type referred to hereinbefore, the receiving unit would be an inductor mounted on a train in inductive relation with the track rails. The first and second stages of amplification include electron tubes 2 and 3, respectively. As here shown, tubes 2 and 3 are of the indirectly heated cathode type, the filament of each of the tubes being constantly heated in the usual manner. Receiving unit IC is coupled to control grid 5 and cathode 6 of the first stage tube 2 through a transformer T1, the alternating current grid circuit for tube 2 being completed through a biasing unit BU1, ground electrodes 7 and 8, a condenser C2, and a winding of transformer T1. Biasing unit BU1 preferably includes an adjustable resistor 30 in multiple with a condenser 31. Plate voltage is provided for plate 9 of tube 2 from a source whose terminals are indicated at B300 and N300, such plate circuit preferably including terminal B300, resistor 10, impedance 11, another resistor 12, winding 13 of a transformer T2, plate 9 and intervening tube space to cathode 6 of tube 2, biasing unit BU1, ground electrodes 7 and 14 and terminal N300. A condenser 15 is connected across at least a portion of winding 13 of transformer T2 and winding 13 in multiple with condenser 15 are coupled through a condenser 17 to the grid circuit of the second stage tube 3.

According to my invention, a control unit VI, comprising a resistor R2 and a condenser C1 in multiple, is interposed in the grid circuit of the second stage tube 3, such grid circuit including control grid 16 of tube 3, a resistor R1, control unit VI, ground electrodes 19 and 7, biasing unit BU1 and cathode 18 of tube 3. Furthermore, the control unit VI is connected to the grid circuit of the first stage tube 2 through a connection including resistor R3 connected between the terminal of unit VI toward control grid 16 of tube 3 and the terminal of the winding of transformer T1 interposed in the grid circuit of tube 2. The function of control unit VI and this connection including resistor R3 will be explained more fully hereinafter.

The plate circuit for the second stage tube 3 extends from terminal B300 through resistor 10, impedance 11, resistor 12, winding 20 of a transformer T3, plate 21, intervening tube space to cathode 18, biasing unit BU1 and ground electrodes 7 and 14 to terminal N300. It is to be seen that each tube 2 and 3 is provided with a normal grid bias voltage derived from unit BU1, the magnitude of such bias voltage being predetermined by the setting of the resistor 30. As here shown, tubes 2 and 3 are provided with screen grids 22 and 23, respectively, and each of which screen grids is connected to the cathode of the associated tube. Also, other screen grids 24 and 25 of tubes 2 and 3, respectively, are supplied with a positive voltage from the B300-N300 current source in the usual manner as will be apparent from an inspection of Fig. 1.

The plate circuit of tube 3 is coupled to the in-

put side of a demodulator DO by transformer T3, whose winding 20 is included in the plate circuit of tube 3 and whose windings 26 and 27 are connected to demodulator DO. The specific construction of demodulator DO is immaterial and it is shown conventionally for the sake of simplicity. For example, demodulator DO may be of the balanced type covered by Letters Patent of the United States No. 2,129,313, granted September 6, 1938, to L. D. Whitelock, for Apparatus for electric signaling systems. It is sufficient for this application to point out that in demodulator DO a carrier is mixed with the side band telephone current appearing in windings 26 and 27 of transformer T3 and the voice frequencies appear in winding 28 of a transformer T4, the carrier and the other products of demodulation being eliminated at the demodulator and at a band pass filter BPF.

The voice frequencies appearing in the output of demodulator DO are further amplified at an audio stage which includes an electron tube 4, preferably of the indirectly heated cathode type, the filament of tube 4 being constantly heated in the usual manner. A grid circuit is connected across control grid 32 and cathode 33 of tube 4 to include a biasing unit BU2 and ground electrodes 34 and 35, and to be coupled to winding 28 of transformer T4 through a resistor RL having an adjustable contact 40. Plate 36 of tube 4 is supplied with voltage from the B300-N300 current source through a winding 37 of a transformer T5 having a winding 38 connected to a loud speaker LS. Consequently, the voice frequencies are amplified at tube 4 and reproduced at loud speaker LS, the voltage applied to tube 4 being predetermined by the setting of the adjustable contact 40 of resistor RL.

The parts of the receiving apparatus for the first and second stages are so proportioned that when input energy above a predetermined magnitude is picked up by the receiving unit IC and amplified at the first stage tube 2, the grid 16 of the second stage tube 3 is caused to swing positive in potential with respect to cathode 18 during at least a portion of each positive half cycle of the received current. During the period grid 16 swings positive in potential, it tends to draw grid current, such current flowing in resistor R2 of unit VI to build up a charge on condenser C1 of a value substantially equal to the average voltage drop across resistor R2, and hence proportional to the magnitude of the grid current and in turn proportional to the magnitude of the input energy. The polarity of the charge thus created on condenser C1 is as indicated by the plus and minus signs placed in Fig. 1. That is to say, the terminal of control unit VI adjacent the ground electrode 19 is positive and the terminal toward control grid 16 of tube 3 and to which terminal the connection including R3 is connected is negative. It is clear that the charge built up on condenser C1 of control unit VI is applied to the control grid 5 of the first stage tube 2 through the connection including resistor R3 and is also applied to the control grid 16 of the associated tube 3, and the polarity of this charge is such as to increase the normal negative grid bias voltage of these tubes derived from the biasing unit BU1, with the result that both tubes 2 and 3 amplify at a less extent when the incoming energy is of a magnitude above the predetermined value. The energy level of the current applied to demodulator DO is therefore made of substantially the same value for input energy of large

magnitude as for input energy of a normal predetermined magnitude. After demodulation, the voltage drop across resistor RL is substantially uniform, and hence the voltage applied to control grid 32 of the final stage tube 4 is predetermined by the setting of contact 40 of resistor RL . Consequently, the output volume of the loud speaker LS can be governed by manually adjusting the position of contact 40 along resistor RL .

In Fig. 2, curves plotted between volts input and current output are illustrated. Curve B is that attained by the receiving apparatus through automatic control unit VI and its associated connection as shown in Fig. 1. It is to be noted that an output of about 250 milliamperes is quickly reached as the input voltage reaches a normal predetermined value of about .001 volt and the output current remains at substantially the same level for input voltages of larger magnitude. The dotted line curves B_1 and B_2 are curves resulting when the manually controlled resistor 30 of biasing unit BU_1 is set to effect larger normal bias voltages for tubes 2 and 3. The curve A illustrates the slope of the volume control obtained when a receiving amplifier is provided with the usual form of automatic volume control means including a rectifier in the output of the low frequency stage to rectify a portion of the output current to produce a voltage which is applied to the grid of the earlier stages in the usual manner.

I have found by test that there is little distortion introduced at the earlier stages by the automatic volume control of my invention. In cases of a relatively low or normal value of input voltage (see Fig. 3) the normal grid bias voltage (EG) is such that the resultant amplified current (IP) is without distortion as illustrated in Fig. 3. At higher values of input voltage the volume control acts to shift the bias voltage almost immediately so that, as illustrated in Fig. 4, the bias voltage on the first tube is shifted from EG_1 to EG_2 and the amplified current therefrom is still without distortion.

It is to be understood that the receiving apparatus of Fig. 1 can include additional stages of high frequency amplification and additional stages of low frequency amplification if desired.

Receiving apparatus here disclosed has the advantages that the normal bias voltage can readily be predetermined by means of adjustable unit BU_1 to bring out the voice current over noise energy that may be present. Resistor RL can be adjusted to apply a voltage to the final stage to cause a desired volume of the loud speaker output as required to be heard above local noise, as might be the case in the cab of a railway locomotive. Also the automatic volume control effected by unit VI rises to a high value quickly on input voltages over a predetermined value and the output energy level is held at a substantially uniform level. Furthermore, the automatic volume control causes little distortion of the output energy.

Although I have herein shown and described but one form of receiving apparatus for communication systems embodying my invention, it is understood that various changes and modifications may be made therein within the scope of the appended claims without departing from the spirit and scope of my invention.

Having thus described my invention, what I claim is:

1. In receiving apparatus for a communication

system using an oscillating current, the combination comprising; a first and a second stage of amplification each of which stages includes an electron tube having a plate, a cathode and a control grid; a grid circuit for said first stage tube and including a winding disposed to receive such oscillating current and a biasing unit having an adjustable resistor, a grid circuit for said second stage tube including said biasing unit and a control unit having a resistor and a condenser in multiple, a plate circuit for each of said tubes and each of which plate circuits includes a source of direct current and said biasing unit, means to couple the first stage tube plate circuit to the second stage tube grid circuit, said biasing unit having one terminal connected to the cathodes in multiple of the first and second stage electron tubes to provide a normal negative grid bias voltage for each of said tubes due solely to the plate currents flowing in such unit and which voltage is of a value predetermined by adjustment of said adjustable resistor, said control unit having one terminal connected to the control grid of the second stage tube and its other terminal connected to the cathode of the second stage tube through said biasing unit to create a charge across the condenser of the control unit when the oscillating current received by said winding and amplified by said first stage tube drives the second stage tube control grid positive in potential with respect to the cathode and grid current flows, and means including another resistor to connect said control unit to the grid of said first stage tube to increase its negative grid bias voltage by the charge of said condenser.

2. In receiving apparatus for a communication system using a carrier telephone current, the combination comprising; a first and a second stage of high frequency amplification, a demodulator and a stage of audio frequency amplification; each of said stages including an electron tube having a plate, cathode and a control grid; a first grid circuit including a receiving unit adapted to pick up such telephone current and connected to the grid and cathode of said first stage tube, a second grid circuit including a control unit comprising a resistor and a condenser in multiple and connected to the grid and cathode of said second stage tube, a plate circuit for each of said first and second stage tubes and including a common biasing unit to provide a predetermined normal grid bias voltage for each of the first and second stage tubes, means to couple the plate circuit of the first stage tube to the grid circuit of the second stage tube, a circuit connection to connect a given terminal of said control unit to the grid circuit of the first stage tube to apply an automatic volume control voltage to the first stage tube when telephone current of large magnitude is picked up and grid current flows in the grid circuit of the second stage tube to charge the condenser of said control unit, means to couple the plate circuit of said second stage tube to said demodulator, a third grid circuit including a winding and an adjustable resistor in multiple connected to the grid and cathode of said audio stage tube, means to couple said winding to said demodulator to apply a voltage to said audio stage tube as predetermined by said adjustable resistor, and a loud speaker coupled to the plate circuit of said audio stage tube.

WARREN M. ADAMS.
